UNITED STATES PATENT OFFICE.

EDWARD H. REMDE, OF CLEVELAND, OHIO, ASSIGNOR TO THE BAKER MOTOR VEHICLE COMPANY, OF CLEVELAND, OHIO, A CORPORATION OF OHIO.

DESIGN FOR A VEHICLE-BODY.

45,021.

Specification for Design.

Patented Dec. 9, 1913.

Application filed September 22, 1913. Serial No. 791,233. Term of patent 7 years.

To all whom it may concern:

Be it known that I, EDWARD H. REMDE, a citizen of the United States, residing at Cleveland, in the county of Cuyahoga and State of Ohio, have invented a new, original, and ornamental Design for a Vehicle-Body, of which the following is a specification, reference being made to the accompanying drawing, forming a part thereof.

Figure 1 is a side elevation of a vehicle body showing my new design. Fig. 2 is a

top plan view thereof. Figs. 3 and 4 are front and rear views, respectively, of the vehicle body.

I claim:

The ornamental design for a vehicle body, as shown.

EDWARD H. REMDE.
